United States Patent Office.

BENJAMIN P. PENDEXTER, OF MINOT, ASSIGNOR TO HIMSELF AND GEORGE W. HORNER, OF MECHANIC'S FALLS, MAINE.

Letters Patent No. 78,995, dated June 16, 1868.

IMPROVEMENT IN MACHINE FOR SHARPENING SAWS.

The Schedule referred to in these Letters Patent and making part of the same.

TO ALL WHOM IT MAY CONCERN:

Be it known that I, BENJAMIN P. PENDEXTER, of Minot, in the county of Androscoggin, and State of Maine, have invented a new and improved Circular File and Saw-Set; and I do hereby declare that the following is a full, clear, and exact description thereof, which will enable others skilled in the art to make and use the same, reference being had to the accompanying drawings, forming part of this specification.

This invention relates to an improved machine for filing and setting saws, and it consists in the construction and combination of devices to be hereinafter described. In the drawings—

Figure 1 is an end view of the machine to which my invention is applied.

Figure 2 is a front view of the same.

Figure 3 is a view of the end opposite fig. 1.

Figure 4 is a side elevation of the circular file, and

Figure 5 a central vertical section in the line $x x$, fig. 4.

B is the frame of the machine, bearing in its upper end the arbor C, connected to operate with the crank-shaft S¹, by means of the pulleys D D' and belt E, as shown. The crank-shaft S¹ is provided with a fly-wheel, W, and is operated by a treadle, t, connected to the crank by means of the rod t'. This construction will be readily understood by reference to the drawings, and therefore requires no special description.

Upon one end of the shaft C, outside the frame B, is mounted an annular file, a, shown in section, fig. 5. The file is rebated out upon one of its inner edges, to receive the flange of an annular metallic washer fitting upon the hub A of the shaft, and secured thereto by means of metallic washers or disks.

The opposite end of the shaft revolves in bearings, whose upper metallic portion is provided with an upwardly-projecting anvil, e, to receive the teeth of the saw, and extended laterally for the reception of the adjusting-screw e², by the raising or lowering of which the required set is given to the saw. This portion of the bearing, the anvil, and lateral extension, are all cast in one piece.

Pivoted at e³, upon the top of the frame B, is an arm, S, whose free end forms a hammer, and reaches forward between the guides e¹ e⁴ of the anvil. This arm is provided in rear of the hammer with a start, which is operated by a toe, a², upon the shaft C, to raise the hammer for the necessary blows to be given the saw-teeth. The force of the blows is increased by the tension of a spring, S², attached to the arm S, and any suitable part of the main frame.

The guides e¹ serve as a gauge to give the same length of bend to each saw-tooth. T T' represent the table, supported and adjusted in the bracket f upon the side of the frame, under the circular file a, by means of a set-screw, n. This table is composed of two parts, the upper part T' of which slides backward and forward upon the lower part T, and is adjusted by means of set-screws a² in the latter, working through slots in the said upper part. This part also has a flange on its inner edge, against which the saw to be filed is placed, to prevent the file a from cutting deeper at one time than another.

The eye in the bracket f, for the reception of the shank of the table, is bevelled internally, to admit of the table being adjusted at any desired angle with relation to the circular file.

Constructed as above described, my invention forms a convenient machine for filing and setting saws, the advantages of which are, that the filing is done rapidly and accurately, and the saws quickly and perfectly set.

Having thus described my invention, what I claim therein as new, and desire to secure by Letters Patent, is—

1. The annular file a secured to the flanged wheel A, upon the arbor C, by means of the flanged washers H, as herein described for the purpose specified.

2. The anvil e, for the saw-set, formed upon and with the journal-box of the arbor C, as herein shown and described.

3. In combination with the anvil e formed with the journal-box, the pivoted hammer-arm S, operated by the toe a², and spring S², as herein described for the purpose specified.

BENJ. P. PENDEXTER.
